DESIGN FOR A TOY TRAIN

Joseph P. Tysdal, Fergus Falls, Minn.

Application August 4, 1934, Serial No. 52,814

Term of patent 3½ years

To all whom it may concern:

Be it known that I, Joseph P. Tysdal, a citizen of the United States, residing at Fergus Falls, in the county of Otter Tail and State of Minnesota, have invented a new, original, and ornamental Design for a Toy Train, of which the following is a specification, reference being had to the accompanying drawing, forming part thereof. The toy train is made of wood, with the design painted on the sides and top of same in contrasting colors.

Figure 1 is a side elevation of a toy train showing my new design, the view being broken into

sections in view of the length of the train, the appearance of the opposite side of the units of the train being identical with that of the side shown; and

Fig. 2 is a top plan view of a portion of the train to show the ornamental design of the top portion of the particular elements and also to show the thickness of the wooden cars and locomotives which constitute the train.

I claim:

The ornamental design for a toy train, as shown and described.

JOSEPH P. TYSDAL.
